UNITED STATES PATENT OFFICE.

DANIEL V. SHERBAN, OF CANTON, OHIO.

PULVERIZING MILL.

REISSUED

1,427,234.

Specification of Letters Patent. Patented Aug. 29, 1922.

Application filed December 23, 1921. Serial No. 524,524.

To all whom it may concern:

Be it known that I, DANIEL V. SHERBAN, a citizen of the United States, residing at Canton, in the county of Stark and State of 5 Ohio, have invented certain new and useful Improvements in Pulverizing Mills, of which the following is a specification.

My invention relates to improvements in machines having for their purpose the 10 crushing or pulverizing coal or other similar material. It has for its object to effect the pulverization and gradation of a suitable substance, as coal, and to provide a machine for such purpose in which the coal 15 is delivered into a rotatable drum and subjected therein to the crushing and pulverizing action of series of loose balls operating upon the coal by gravity and centrifugal action as the drum revolves.

20 One particular feature of novelty involved is in providing means for screening and carrying off the fine dust, as it is produced, from the interior of the drum, and for maintaining and protecting such means, together with various other features of construction and operation, as shall be more 25 fully hereinafter described.

In the drawings,

Fig. 1 is a view in longitudinal section, 30 partly in elevation, showing a complete apparatus as assembled;

Fig. 2 is a cross section on line II—II of Fig. 1;

Fig. 3 is a diagrammatic view showing 35 a rotatable grinding barrel in cross section, showing the action of the balls within an uninterrupted area;

Fig. 4 is a similar view showing the novel effect of introducing the interfering screen; 40 and

Fig. 5 is an enlarged sectional detail view of a portion of the central screen.

The main operative member of the crushing apparatus consists of a rotatable drum 45 or tumbling barrel 2, the heads or ends 3—3 of which are mounted in suitable bearings 9—9 by means of the hollow trunnion extensions 4—4. The receiving end of the drum communicates through one of said 50 trunnion extensions with a supply pipe 5, to which lump coal is delivered by conduit 6 leading from a hopper terminal 7 or other source of supply. The conduit 5 has a valve controlled terminal 8 at any 55 suitable inlet point for the reception of atmospheric air.

The other head 3 is similarly mounted by its trunnion 4 in the opposite bearing 9 and communicates through the said trunnion with a suction or exhaust fan 10 actuated by a suitable driving motor, adapted to collect the dust as produced, and having a delivery conduit 11 leading to a furnace or other point of consumption or storage.

60 The interior of the drum 2 may be continuously open from end to end, or may be divided into a series of sectional compartments *a*, *b*, respectively, divided by an annular partition wall 12 extending transversely across the drum area and serving to retain the series of crushing balls 13 in place. Longitudinal strips or abutments 14 extend at intervals throughout the length of the inner circumference of the drum, in 70 the manner of slats or ridges, and with centrifugal force, have the function and effect of partially lifting the balls and dropping them as the drum rotates in carrying out its work of crushing and grinding the coal. 75

Extending inwardly through the central portion of the drum near its receiving end, is a cylindrical screen 15 communicating with the intake end of fan 10 through the trunnion 4 of the drum. The screen may 80 be formed of comparatively fine mesh screen so as to prevent the passage therethrough of any particles of coal not sufficiently small to use as pulverized fuel, or may be otherwise made so as to admit to its interior only 85 such fuel as is sufficiently fine to be utilized with an air feed column. In the drawings, the cylinder is shown as of comparatively heavy sheet or plate metal, extending into the suction conduit at its delivery end and open 90 for inflow of pulverized material throughout its length clear to the opposite end. Screen 15 is supported within the trunnion 4 by extended rods 16. Cylinder 15 is provided throughout its body portion with 95 series of longitudinally arranged slots or openings 17 comparatively narrow at their outer portions and enlarging inwardly by a widening taper, as shown. By this means, the entrance opening controls the size of 100 the fuel, and prevents a tendency to clog the slots.

The supply of air is preferably controlled through an adjustably mounted air inlet valve 18 of casing suitably connected by rod 110 19 and a sheave-guided cord 20 with a rheostat 21.

The function of the central screen 15 is two fold. It acts to collect by suction all of the sufficiently fine fuel as made and to carry it off through conduit 11, and also acts as 5 a middle barrier for the crushing balls. These ordinarily pass around with the drum and are carried upwardly by the slats or by centrifugal force, or both, and are dropped directly back into the contents of the drum, 10 as in Fig. 3. By interposing the screen 15 in the middle of the drum, it is directly in the path of the falling balls, as in Fig. 4. The resulting effect is that the stream of falling balls is divided and passes downwardly at each side. Those balls which fall toward the main rising stream of balls at the ascending side of the drum are engaged frictionally thereby, and the result is that 15 a small cyclonic zone X is induced with a resulting rotary path of travel, as indicated by the arrows. The effect is to greatly accelerate the grinding and pulverizing action, and this is increased by using a mass of balls 20 of varying size in the common interior of the drum. The balls which pass over to the other side of the screen are somewhat spread apart and more freely distributed, and there is thus a constant tendency to improve the grinding action. A further advantage is 25 that the constant hammering of the balls on the central screen tends to dislodge any adhering particles, thus keeping the slots 17 open and unobstructed.

The drum may be rotated in any suitable 30 way, as by a pinion 22 engaging an annular rack 23, the speed of rotation being suitably controlled by the driving gearing.

The construction and operation of the invention will be readily understood and appreciated from the foregoing description. The machine is capable of continuous and successful operation in the manner intended, without liability of getting out of order, and is well adapted to perform its intended 40 functions in continuously pulverizing the coal and delivering the pulverized fuel in continuously uniform grade.

The machine may be built in different sizes to suit local requirements, or variously changed in detail construction or other- 45

wise by the skilled mechanic, but all such changes are to be considered as within the scope of the following claims.

What I claim is:

1. A grinding mill consisting of a rotatable drum provided with grinding balls and a central axially arranged suction screen having a continuous uninterrupted receiving cavity from one end to the other. 55

2. A grinding mill consisting of a rotatable drum provided with grinding balls, a central axially arranged suction screen having a continuous uninterrupted receiving cavity from one end to the other, means providing an extracting current therethrough, 60 and means for introducing raw material to the drum. 65

3. In combination, a rotatable drum, means for introducing raw material and air to one end thereof, a central axially arranged cylindrical screen extending inwardly of the drum from the other end thereof having a continuous uninterrupted receiving cavity from one end to the other, and a suction fan and exhaust conduit communicating therewith. 70

4. In combination, a rotatable drum, means for introducing raw material and air to one end thereof, a centrally arranged cylindrical screen extending inwardly of the drum from the other end thereof provided with inwardly enlarging circulation openings and a continuous interior receiving cavity, and a suction fan and exhaust conduit 75 communicating therewith. 80

5. In combination, a rotatable drum having terminal hollow trunnions for inlet of raw material and air and outflow of pulverized material and air, a suction fan connected with the outflow trunnion, a central axially arranged suction screen extending from the outflow trunnion inwardly of the drum towards the receiving trunnion having a continuous open interior, means for supporting the screen, and a series of grinding balls in the drum. 90

In testimony whereof I hereunto affix my signature.

DANIEL V. SHERBAN.
